(57) **CLAIM**

The ornamental design for a three dimensional shark fin vehicle ornament, as shown and described.

DESCRIPTION

FIG. 1 is a perspective view of the three dimensional vehicle ornament of the present invention;

FIG. 2 is a view of the left side of the three dimensional vehicle ornament of the present invention;

FIG. 3 is a view of the right side of the three dimensional vehicle ornament of the present invention;

FIG. 4 is a front view of the three dimensional vehicle ornament of the present invention;

FIG. 5 is a rear view of the three dimensional vehicle ornament of the present invention;

FIG. 6 is a top view of the three dimensional vehicle ornament of the present invention; and,

FIG. 7 is a bottom view of the three dimensional vehicle ornament of the present invention.

In the drawings, the broken lines in FIG. 7 depict portions of the article that form no part of the claim.
